UNITED STATES PATENT OFFICE.

FRANCIS HENRY WHITEHOUSE, OF SHEFFIELD, ENGLAND.

DESIGN FOR A SHIRT-FRONT.

SPECIFICATION forming part of Design No. 32,909, dated July 3, 1900.

Application filed February 12, 1900. Serial No. 5,031. Term of patent 14 years.

To all whom it may concern:

Be it known that I, FRANCIS HENRY WHITEHOUSE, a subject of the Queen of Great Britain, residing at 33 Fargate, Sheffield, in the county of York, England, have invented and produced a new and original Design for Shirt-Fronts, of which the following is a specification, reference being had to the accompanying drawing, forming part thereof.

10 The design consists in the outline configuration of the shirt-front.

The essential feature consists in the projections A B, two of which are at each end of the flat sheet C, forming the body portion of 15 my design. The projections of each pair in-

cline toward each other, and there is a recess in the edge of the sheet between these two projections, said recess having a sinuous edge. The corners of the sheet are rounded, as at E, and the sides are bounded by sinuous lines. 20

I claim—

The design for a shirt-front as herein shown and described.

In witness whereof I have hereunto set my hand in presence of two witnesses.

FRANCIS HENRY WHITEHOUSE.

Witnesses:

ROBERT FRANCIS DRURY,
ENSOE DIXIE DRURY.
